UNITED STATES PATENT OFFICE.

BEN KING FORD, OF DETROIT, MICHIGAN, ASSIGNOR TO DETROIT CAN COMPANY, OF DETROIT, MICHIGAN, A CORPORATION OF NEW JERSEY.

PROCESS OF MAKING PAPER-WALLED CANS.

1,188,432.

Specification of Letters Patent. Patented June 27, 1916.

Application filed September 20, 1912. Serial No. 721,360.

To all whom it may concern:

Be it known that I, BEN KING FORD, a citizen of the United States, residing in Detroit, in the county of Wayne and State 5 of Michigan, have invented a new and useful Improvement in Processes of Making Paper-Walled Cans, of which the following is a specification.

This invention relates to a process of 10 making paper walled cans suitable for containing milk or food products. And the invention consists in the series of steps or acts done, as hereinafter more fully set forth and made the subject matter of claim.

15 In the accompanying drawing which forms a part of this specification, Figure 1 is a diagrammatic side elevation to illustrate the method of coating the paper, of which the walls are formed, with the fused cement 20 adhesive, and applying the supplemental lining sheet thereto; Fig. 2 is a plan view of the same; Fig. 3 a side elevation of the winding mandrel and heating table; Fig. 4, a plan of said mandrel and table; Fig. 5, 25 a section of the winding mandrel; Fig. 6, a view of the wound product before being cut up into lengths; and Fig. 7, a fragmentary section of the wound product, upon an enlarged scale, to illustrate the construction.

30 In practising this process for the manufacture of cans or vessels suitable for holding milk or other food products, a long sheet of paper, which may consist of ordinary cheap, turpentine log pulp paper, and which should be of a width several times the circumference of the cylindrical vessel or can that is to be produced, is coated on one side with melted asphaltum or other 35 similar fusible cement adhesive. On one edge of this coated sheet is laid upon the fused cement and pressed thereon a narrower strip of lining paper, preferably hard 40 finish sulfite spruce pulp paper, which may subsequently be brought into contact with 45 milk or other food product without imparting any taste thereto, which strip is to constitute the lining of the walls of the can or vessel to be produced. This composite 50 sheet, consisting of the sheet of cheap paper coated on one side with the fused cement and carrying the narrower sheet of lining paper adherent thereto, is cut into short 55 lengths equal to a length of the intended can or a multiple of that length. After the cement has become cold and hard, these

shorter lengths, the cement being reheated, are, each one, to be wound upon a mandrel in such manner as to bring the lining sheet next to the mandrel which it should completely encircle, the continued winding bringing the remainder of the coated sheet upon the mandrel with its cemented side toward the already wound portion until all is wound. The tube thus formed, if not already of proper length for the walls of a can, is cut to such proper length, and thereafter, sheet metal ends are applied and crimped to the walls so formed, and the product will be a can or vessel suitable for containing any food product or milk, and also of such constitution that the contents may be heated in the can itself for the purpose of sterilization or processing without 60 destroying the vessel or injuring the contents. 65

In said drawing, A represents the material out of which the coated sheet is to be formed.

B is a tank of melted asphaltum or cement, B¹ showing the cement itself.

C is a roller turning in the melted cement.

D is a transfer roller for carrying a coat of the cement to the sheet A, where it passes over the guide roll E.

F is a roll of the narrow lining paper fed over the roll E onto the paper sheet A and between the paper and the roll G.

H, H, H, H, are feed and guide rollers.

90 At the right of Fig. 2 is shown by the lines J, J the place where the compound sheet A is cut up into sizes suitable for winding on the mandrel. One of these pieces is shown at Figs. 3 and 4, in which A is the sheet of coated paper and F the sheet of lining paper. In these latter figures, K is a heated table upon which the sheet A and its adherent lining piece F are laid preparatory to being wound upon the mandrel L, which 95 mandrel may be provided with the ordinary suction grip 1.

M is a heating roll between which and the mandrel L the paper is held while being 100 wound upon the latter.

In Fig. 7, A are the outer layers of paper, F is the inner layer of lining paper and B¹ the intercalated layers of fusible cement or asphaltum.

110 I claim:

1. The process of making paper walled vessels, which consists in first forming a

composite sheet composed of a layer of fibrous material coated with moisture-proof fusible cement and having adherent thereto along one edge a narrow strip of lining material, which covers the said coating at one margin of the sheet and leaves exposed the remainder of said coating, and then winding said composite sheet with the lining material on the inside around a mandrel, 16 while the cement is in a fused condition.

2. The process of making paper tubes, which consists in coating a long, wide strip of paper with fused cement, uniting thereto by means of said cement along one edge a 15 narrow strip of lining paper, cutting the composite sheet so formed into transverse smaller sheets and thereafter reheating the coating of cement and winding the smaller sheets upon a mandrel.

20 3. The herein described process which consists in coating a web of fibrous material with a moisture-proof fusible cement and applying to a margin of the sheet over the said coating a strip of material adapted to 25 form a lining, and which leaves exposed the remainder of said coating, and then winding the composite member thus formed with the lining material on the inside, and during the winding step applying heat to there- 30 by fuse the cement.

4. The process of making paper tubes which consists in coating a long wide sheet

of paper with fused cement, uniting thereto by means of said cement along one edge a narrow strip of lining paper, and thereafter 35 reheating the coating of cement and winding the composite sheet upon a mandrel so that the edge of the lining paper which extends across the median portion of the sheet shall be substantially parallel with the axis 40 of the mandrel and so that the lining paper shall be in contact with the mandrel and form the interior surface of the tube.

5. The process of making tubes which 45 consists in passing a strip of paper in a direction parallel with its length and coating the same with fused cement; uniting thereto by means of said cement along one edge a narrow strip of lining paper which covers a portion of the said cement; then passing 50 the composite sheet so formed in a direction transverse to the first mentioned direction at the same time reheating the fused cement, and winding the said composite sheet upon a mandrel so that the said lining paper 55 covers the mandrel and keeps the fused cement out of contact with the mandrel, the fused cement being caused to adhere to the back of the composite sheet where it comes in contact with the same.

BEN KING FORD.
